UNITED STATES PATENT OFFICE.

ALFRED F. MEYER, OF MORTON, ILLINOIS, ASSIGNOR TO A. F. MEYER MANUFACTURING CO., OF MORTON, ILLINOIS, A CORPORATION OF ILLINOIS.

COMBINED DUMP AND ELEVATOR.

1,165,109.

Specification of Letters Patent.

Patented Dec. 21, 1915.

Application filed February 5, 1913. Serial No. 746,318.

To all whom it may concern:

Be it known that I, ALFRED F. MEYER, a citizen of the United States, residing at Morton, in the county of Tazewell and State of Illinois, have invented certain new and useful Improvements in Combined Dumps and Elevators, of which the following is a specification.

My invention relates to improvements in combined dump and elevators and particularly to the driving mechanism therefor.

The principal object of my invention is the provision of a driving mechanism for a combined dump and elevator so arranged that the source of power is located on the side of the elevator opposite the dump and having connections whereby the elevator and dump may be separately clutched in driving relation to said source of power, as desired, but whereby the dump and elevator may not be simultaneously connected with the source of power.

To the accomplishment of the foregoing and such other objects as may hereinafter appear my invention consists in the construction, combination and arrangement of parts hereinafter described and then sought to be defined in the appended claims, reference being had to the accompanying drawings forming a part hereof and which show for the purposes of illustrative disclosure, two embodiments of my invention, it being expressly understood that minor changes may be made within the scope of the claims without digressing from my inventive idea.

In the drawings: Figure 1 represents a diagrammatic view showing, in elevation, part of a power device, part of a dump with an elevator located therebetween, the operative connections being constructed according to my invention; Fig. 2 is a front elevation of the lower portion of the elevator shown in Fig. 1 showing the operative connections; Fig. 3 represents a side elevation of the lower portion of the elevator and connections, looking at the right hand side of Fig. 2; Fig. 4 is a view similar to Fig. 3, showing a slightly different driving connection for the elevator, and, Fig. 5 is a vertical section of part of the elevator and dump shafts and the clutch mechanism.

Generally speaking, my invention includes a source of power, an elevator and a dump, with connections whereby the elevator and the dump may be operated separately from

the source of power but never simultaneously. These connections include a shaft for operating the dump and a clutch device for operatively connecting it to the driving shaft from the source of power. This driving shaft has a sprocket loosely mounted thereon having a connection to drive the elevating mechanism, the same clutch device being adapted to operatively connect the sprocket to the driving shaft. Said clutch device is so arranged that when the dump is operatively connected to the driving shaft, the elevator will not be connected, and vice versa.

Referring now to the drawings, the numeral 1 designates the source of power which is illustrated as being in the form of a conventional type of horse power it being understood however that I may utilize any desirable source of power or motor. The driving shaft 2 is operated by the motor 1, having the universal joints 3 connecting it to the shaft 4 extending through the boot 5 of elevator 6. The construction of this elevator is not shown in detail as it may be of any type, portable or permanent, or built for exterior or interior use. In the form shown it includes the boot 5, vertical leg portions 7 having the conveyer chains 8 with the buckets 9 thereon running therein. The chains 8 run over sprockets 10 on shaft 11 at the upper end of the leg of the elevator and over sprockets 12 which are loosely mounted on shaft 4 in the boot of the elevator. Shaft 11 is driven by means of the sprocket chain 13 engaging the sprocket wheel 14 on its outer end, said chain also running over sprocket wheel 15 which is loosely mounted on shaft 4 outside of the boot of the elevator and is adapted to be clutched to said shaft by the operator. The sprocket wheel 16 is provided to operate a conveyer in drag 17, which is only partially shown.

The shaft 4 is suitably supported in bearings in the sides of the boot of the elevator, its end terminating in juxtaposition and alignment with the dump driving shaft 18 which is supported by the bracket member 19 and is adapted to drive the dump 20, parts of which only are shown, as the details thereof do not constitute features of this invention, which may be used with any form of dump.

As a means of connecting either the ele-

vator or dump mechanism in operative relation with the power, I provide the form of clutch construction shown in Fig. 1 and in enlarged detail in Figs. 2 and 5. As stated hereinbefore, sprocket wheel 15 is loosely mounted on shaft 4 and further is provided with the hub portion 21 having the clutch face 22. The dump driving shaft 18 has fixedly secured thereon the member or collar 23 having the clutch face 24. The ends of the shafts 4 and 18 are in close proximity so that the clutching member or sleeve 25 extends over the end portions of both shafts. This sleeve 25 has the clutch faces 26 corresponding and facing the clutch faces 22 and 24, and is slidably mounted on shaft 4 by means of the slot and key connection 27. As shown in Fig. 5, this key 27 extends against the hub portion 21 of the sprocket wheel 15 so as to hold said sprocket wheel in its proper position. The sleeve 25 is grooved as at 28, to receive the yoke member 29 of the operating lever 30, the latter being pivoted to the bracket member 19, as at 31. As the clutching member or sleeve 25 is keyed to the shaft 4 which is always connected to the driving shaft 2 of the motor or power 1, it is obvious that its movement in one direction will clutch the sprocket wheel 15 in operative relation to said driving shaft so as to drive said elevator, and that its movement in the other direction will break said operative connection between the driving shaft and the elevator and clutch the dump driving shaft 18 in operative connection with the driving shaft 2 so as to operate the dump, and vice versa.

The construction shown in Fig. 4 is substantially the same, differing in that the driving shaft is mounted outside of the boot, the sprocket wheels 12' being fast on shaft 4' in the boot of the elevator which is driven by means of sprocket wheel 14', sprocket chain 13' and sprocket wheel 15' which is adapted to be operatively connected to the source of power in substantially the same manner as sprocket wheel 15, it being understood that said sprocket wheel 15' is normally loose on the driving shaft.

This invention is advantageous for the reason that it may be readily used with motors of small power where the motors cannot operate the dump and elevator simultaneously. It frequently happens that the motor of the operator has not the power for the combined operation, but has the power to operate the dump and elevator separately. In addition, there is no unnecessary wear and tear on the parts due to useless operation and running, as the elevator and dump may be run separately, as desired.

What I claim is:

1. In combination with a motor, an elevator and a dump, a driving shaft connected to the motor, a shaft for driving the dump,

said dump driving shaft being normally out of connection with said driving shaft, a driven element loosely mounted on said driving shaft and adapted to operate said elevator, said element having a clutch face, a member having a clutch face on said dump driving shaft, a clutching member slidably connected for rotation with said driving shaft and positioned between said driven element and said first mentioned member, said clutching member having clutch faces corresponding to the clutch faces on said element and said first mentioned member, and means for moving said clutching member, said clutching member being adapted to connect said driven element in operative relation with said driving shaft, said means being also adapted to connect said dump driving shaft in operative relation with said driving shaft, said means being so constructed that when one of said connections is made the other connection cannot be made without breaking said first mentioned connection, and vice versa.

2. In combination, a motor, an elevator and a dump, a driving shaft connected to the motor, a shaft for driving the dump, said dump driving shaft being normally out of operative connection with said driving shaft, a sprocket wheel loosely mounted on said driving shaft and having a chain and sprocket connection with said elevator, said sprocket wheel having a clutch face, a collar mounted adjacent the end of said dump driving shaft and having a clutch face, a clutch sleeve having clutch faces on its opposite ends corresponding to the clutch faces on said sprocket wheel and said collar respectively, said clutch sleeve being slidably keyed to said driving shaft and adapted to clutch either said sprocket wheel or said collar in operative relation to said driving shaft.

3. In combination, a motor, an elevator and a dump, a driving shaft connected to the motor, a shaft for driving the dump, the end of said driving shaft and said dump driving shaft being in alinement and juxtaposition with each other and normally out of operative connection, a driven element loosely mounted on said driving shaft and having permanent connections to drive said elevator, said element having a clutch face, and being located adjacent one end of said driving shaft, a collar secured adjacent one end of the dump driving shaft, said collar having a clutch face, a clutching member positioned over the contiguous end portions of said driving shaft and said dump driving shaft and having its ends formed with clutch faces corresponding respectively to the clutch faces on said sprocket wheel and said collar, a key and slot connection for slidably connecting said clutching member with said driving shaft, said key bearing

against the end of said driven element to hold it in position, and means to move said clutching member, said clutching member being adapted to connect either said 5 sprocket wheel or said dump driving shaft in operative relation to said driving shaft and being so constructed that when one of said connections is made the other can not be made without breaking said first 10 mentioned connection.

4. In combination, a motor, an elevator and a dump, the elevator being positioned between the motor and the dump, a driving shaft connected to the motor, said driving 15 shaft terminating on the side of the elevator toward said dump, a shaft for driving the dump located in alinement with the end portion of said driving shaft and having its end adjacent the end of said driving shaft, 20 said dump driving shaft being normally out of operative connection with said driving shaft, a sprocket wheel loosely mounted on said driving shaft on the side of the elevator adjacent the dump, connections from said 25 sprocket to drive said elevator, a collar secured adjacent the end of said dump driving shaft, said sprocket wheel and said collar having clutch faces, a clutch sleeve embracing the end portions of said driving 30 shaft and said dump driving shaft, and positioned between said sprocket wheel and said collar, said clutch sleeve having on its ends clutch faces corresponding to the clutch 35 faces on said sprocket wheel and said collar, said clutch sleeve being slidably keyed to said driving shaft, and means to operate said clutch sleeve, said clutch sleeve being adapted to operatively connect either said sprocket wheel or said dump driving shaft 40 to said driving shaft.

5. A driving mechanism for an elevator and a dump, including axially alined shafts the meeting ends thereof being normally disconnected, one of said shafts being the driving 45 shaft, the other of said shafts being the driven shaft, a sprocket wheel loosely mounted on the driving shaft and having a clutch face, a clutch member fixed to the driven shaft, a clutch sleeve straddling the 50 meeting ends of the driving and driven shafts but keyed only to the driving shaft,

said clutch sleeve arranged to be moved into engagement with either said sprocket wheel on the driving shaft or clutch member on the driven shaft, and means for controlling 55 said clutch sleeve.

6. A driving mechanism for an elevator and a dump including a suitable elevator structure and a dump structure, axially alined shafts, their meeting ends being normally disconnected, one of said shafts being the driving shaft and adapted to be driven from a suitable source of power, the other of said shafts being the driven shaft, a sprocket wheel loosely carried on one of said 60 shafts and connections between said sprocket wheel and the elevator mechanism, a clutch member fixed to the other of said shafts, a clutch sleeve straddling the meeting ends of said shafts and keyed only to one of said 65 shafts and adapted to have connection with either said sprocket wheel or said clutch member for communication back to said sprocket wheel or to the shaft carrying the fixed clutch member thereon, as may be desired, and means for controlling said clutch 70 sleeve.

7. A driving mechanism for an elevator and a dump including axially alined shafts, the meeting ends thereof being in juxtaposition and normally disconnected, one of said shafts being the driving shaft and the other the driven shaft, a sprocket wheel loosely mounted on the driving shaft and having a clutch face, a clutch member fixed to the driven 80 shaft, a clutch sleeve straddling the meeting ends of the driving and driven shafts and keyed only to the driving shaft, said key engaging said sprocket wheel on the driving shaft to hold said sprocket wheel against 85 movement longitudinally on said shaft, said clutch sleeve being adapted to be moved into engagement with either said sprocket wheel or said clutch member on the driven shaft and means for controlling said clutch sleeve. 90

In testimony whereof I affix my signature, in presence of two witnesses.

ALFRED F. MEYER.
